Chas. D. Davies

UNITED STATES PATENT OFFICE.

WALTON HARRISON, OF NEW YORK, N. Y.

LOUD-SPEAKING TELEPHONE.

1,140,263.

Specification of Letters Patent. Patented May 18, 1915.

Application filed August 21, 1905, Serial No. 275,107. Renewed October 14, 1914. Serial No. 866,728.

To all whom it may concern:

Be it known that I, WALTON HARRISON, a citizen of the United States, and a resident of the city of New York, borough of Brooklyn, in the county of Kings and State of New York, have invented a new and Improved Loud-Speaking Telephone, of which the following is a full, clear, and exact description.

10 My invention relates to a method of and apparatus for producing, in an electric circuit, current variations of extraordinary degree and analogous to sound waves.

15 My invention is of peculiar value in connection with loud speaking telephones, long distance telephones, relays and repeaters for telephony, and Hertzian wave telephonic transmitters.

20 In the accompanying drawing, forming a part of this specification, the figure represents one form of apparatus embodying my invention, to wit, a loud speaking telephonic transmitter.

25 The device exhibited comprises essentially a circuit containing an arc, and a manometric vapor jet, controllable by sounds, for varying the ohmic resistance of the arc.

30 A vibratory diaphragm 1 made of pig-skin, sheet mica, soft rubber or thin metal, is mounted within a casing 2, which is provided with a mouthpiece 3, and supported upon a stem 4, projecting upwardly from a pedestal 5. Another pedestal 6 is provided with a tubular stem 7, which supports a 35 boiler 8, from which a flexible tube 9 leads to the casing 2. The boiler contains a volatile liquid 10, preferably water, and is heated by a lamp 11, so as to generate vapor. From the casing 2 a flexible tube 12 leads to a nozzle 13, which is supported upon a small stem 14 secured by means of a clamping screw 15. The nozzle 13 is, by virtue of a clamping screw 15, thus adjustable in the general direction of its length, and by means of the 45 clamping screw 15 is also adjustable as to height.

40 A post 16, of hard rubber, is provided with a supporting base 17 and with metallic brackets 18. Electrodes 19, which may be 50 of carbon or metals, are adjustably supported by these brackets. A source of electricity 20, such as a battery of not less than 40 volts, is connected in series with a primary winding 21, and disposed in inductive 55 relation to the latter is a secondary winding 22. These windings together constitute a

transformer, which is of proportions suitable for the currents. The secondary winding 22 is connected with a conductor 23, upon which the perfected current variations 60 are impressed. This conductor may be a telephone line and grounded at 24. Screws 25 are used in adjusting the electrodes. The arc is shown at 26.

65 The operation of my device is as follows:—The lamp is lighted, vapor is generated and the carbons are so adjusted as to maintain an arc of suitable length. For most purposes, including the transmission of articulate speech, I prefer a comparatively 70 long arc, but in other cases the arc may be short. The length of the arc may vary from four or five inches down to a small fraction of an inch, depending upon the materials used for electrodes, the voltage of the primary current, and the particular purpose 75 for which the currents are to be used. The vapor issues from the nozzle and impinges upon the arc. The adjustments are such 80 that the vapor may strike the arc only, or any part thereof, or may also impinge upon one or both of the electrodes, as desired. For many purposes I keep the vapor jet 85 clear of the electrodes.

90 The effect of the vapor is to produce variations in the ohmic resistance of the arc, and also to maintain the arc in a favorable position upon the far side of the electrodes, as indicated. The vapor jet greatly changes 95 the flow of current in the primary circuit. If, now, sounds are directed into the mouthpiece so as to cause the diaphragm to vibrate, variations analogous to sound waves are made in the quantity of vapor issuing from the nozzle, and these variations, acting 100 quantitatively upon the arc, or upon the arc and the electrodes as the case may be, set up corresponding variations in the intensity of the primary current. This being so, and the primary circuit acting inductively upon the secondary circuit, the conductor is impressed with current variations analogous 105 to sound waves, but of much greater power than the variations heretofore produced.

110 The changes wrought in the resistance of the arc are somewhat complex. The vapor from the manometer produces a chilling effect, causing the carbon vapor of the arc to contract in volume. On the other hand the vapor from the manometer is heated, some of it perhaps to the point of dissociation. The net result is that the resistance of the

arc is increased by the contact therewith of the vapor from the manometer.

I do not limit myself to the use of a secondary circuit, for the reason that in the present state of the arc the wiring may be varied indefinitely. Neither do I limit myself to any particular material to be used as electrodes, nor to the employment of any particular vapor or other aeriform body, nor to any specific purpose to which the invention is applicable.

I do not limit myself to the use of an arc, in instances where an equivalent therefor may be employed, nor to a single arc as distinguished from any larger number.

Having thus described my invention, I claim as new and desire to secure by Letters Patent:

1. In an apparatus for the transmission of signals, a circuit including an arc, means for supplying an atmosphere containing hydrogen to said arc, and means for varying such supply according to the signals to be transmitted.

2. In an apparatus of the character described, a circuit including an arc, means for supplying an atmosphere containing hydrogen to said arc, and voice-controlled means for varying such supply according to the signals to be transmitted.

3. In an apparatus of the character described, the combination of a continuous closed electric circuit including an arc, and means including a movable diaphragm for directing toward said arc an aeriform body impressed with variations analogous to sound waves.

4. In an apparatus of the character described, the combination of a continuous closed electric circuit including an arc, and means including a movable diaphragm for directing toward said arc varying quantities of an aeriform body capable of affecting the resistance thereof.

5. The combination, with a source for supplying an aeriform body and means for varying the quantity of said aeriform body, of a continuous electric circuit including an arc the resistance of which is sensitive to variations in the supply of said aeriform body.

6. In an apparatus of the character described, the combination of a continuous closed circuit, mechanism for continuously liberating an aeriform body, means for producing variations in the flow of said aeriform body, and mechanism for causing said aeriform body, thus affected, to vary the resistance of said closed circuit sensitive to the influence thereof.

7. In an apparatus of the character described, the combination of a manometer provided with a vibratory diaphragm for controlling the flow of an aeriform body, and a continuous closed electric circuit the

resistance of which is sensitive to variations in the flow of said aeriform body.

8. In an apparatus of the character described, the combination of a source of aqueous vapor, sound-controlled mechanism for varying the flow of said aqueous vapor, and an electric circuit, the ohmic resistance of which is sensitive to the flow of said aqueous vapor.

9. In an apparatus of the character described, the combination of a continuous dynamical electric circuit provided with an arc across which the current flows, and means for producing an aeriform jet impressing the ohmic resistance of said arc with variations analogous to sound waves.

10. In an apparatus of the character described, the combination of a continuous circuit, a part of which has a variable ohmic resistance under the action of varying quantities of an aeriform body, and means for subjecting said part of said circuit to varying quantities of said aeriform body.

11. In an apparatus of the character described, the combination of a circuit provided with an arc, a source of direct current for energizing said circuit, and means for directing toward said arc a manometric jet of steam impressed with quantitative variations analogous to sound waves.

12. In an apparatus of the character described, the combination of a continuous circuit the resistance of which is changeable by variations in the flow of an aeriform body, means for supplying said aeriform body, and voice-controlled mechanism for producing, in the flow of said aeriform body, variations analogous to sound waves.

13. In an apparatus of the character described, the combination of a continuous closed electric circuit, a portion of which is maintained at a high temperature, and sound-controlled mechanism for directing toward said portion a flowing medium having a lower temperature for the purpose of varying the ohmic resistance of the same.

14. In an apparatus of the character described, the combination of a continuous electric circuit in a part of which the ohmic resistance is sensitive to quantitative variations in temperature, and means for directing upon said part varying quantities of a body capable of varying the temperature thereof.

15. In an apparatus of the character described, the combination of a continuous circuit provided with an arc and with means for normally maintaining said arc steady, and sound-controlled mechanism for subjecting said arc to the action of varying quantities of an aeriform body.

16. In an apparatus of the character described, the combination of a telephone line wire, a continuous circuit for energizing the same, said circuit including an arc, means

- for energizing said circuit so as to constantly maintain said arc, and sound-controlled mechanism for throwing upon said arc varying quantities of an aeriform body.
- 5 17. In an apparatus of the character described, the combination of a telephone line wire, a continuous circuit for energizing the same, said circuit including an arc, a source of direct current for energizing said circuit, thus maintaining said arc steadily, and means for directing toward said arc varying quantities of an aeriform body capable of affecting the ohmic resistance of the same.
- 10 18. In a device of the character described, the combination of a telephone line wire, a secondary winding connected therewith, a primary winding for energizing said secondary winding, an arc lamp and a source of direct current connected with said primary winding, and voice-controlled mechanism for directing toward said arc an unbroken but varying stream of an aeriform body.
- 15 19. In a device of the character described, the combination of a telephone line wire, a circuit for energizing the same, said circuit including an arc lamp, a source of electricity for maintaining said arc unbroken, and mechanism for directing toward said arc an unbroken but varying stream of an aeriform body capable of varying the ohmic resistance of said arc.
- 20 20. In an apparatus of the character described, the combination of a continuous electric circuit provided with an arc, mechanism for directing an aeriform body toward said arc, so as to vary the resistance thereof, and means for adjusting the path of said aeriform body relatively to said arc.
- 25 21. In an apparatus of the character de-
- scribed, the combination of a continuous electric circuit provided with an arc, mechanism for directing an aeriform body toward said arc so as to vary the resistance thereof, and means for adjusting the position of said arc relatively to the path of said aeriform body.
22. In an apparatus of the character described, the combination of an electric circuit provided with electrodes, a source of continuous dynamic electricity connected with said electrodes for forming an unbroken arc therebetween, and means for directing upon said arc a varying but unbroken stream of an aeriform body capable of affecting said arc.
23. In an apparatus of the character described, the combination of an electric circuit provided with an arc, a source of direct current for energizing said circuit so as to maintain said arc, and means controllable by sounds for throwing upon said arc an unbroken but varying jet of steam.
24. In an apparatus of the character described, the combination of a telephone line wire, a continuous circuit for energizing the same, said circuit being provided with a portion the ohmic resistance of which may be varied by the flow of an aeriform body thereagainst, and means for directing against said portion a varying but unbroken stream of said aeriform body.

In testimony whereof I have signed my name to this specification in the presence of two subscribing witnesses.

WALTON HARRISON.
